UNITED STATES PATENT OFFICE.

ISAAC SCHEINMAN, OF NEW YORK, N. Y.

TROUSERS.

1,106,587.

Specification of Letters Patent. Patented Aug. 11, 1914.

Application filed November 15, 1912. Serial No. 731,499.

To all whom it may concern:

Be it known that I, ISAAC SCHEINMAN, a citizen of the United States, and a resident of the borough of Manhattan, in the county of New York and State of New York, have 5 invented certain new and useful Trousers, of which the following is a specification.

My invention relates particularly to what are known as knickerbockers or knee breeches, and it consists in the combining 10 with the flaps or openings usually at the knee, of the described devices, whereby the flaps are held together neatly and firmly and yet in such manner as not to be unduly 15 tight when secured or when a change in the position of the body calls for more space within the band.

Figure 1 shows the lower end of one leg 20 of a pair of knickerbockers embodying my invention. Fig. 2 is a sectional view of the device of Fig. 1. Fig. 3 shows a broad bridge, sometimes used in place of the narrow bridge of Fig. 1.

Knickerbockers or knee breeches are usually 25 open at the knee and have a band adapted to surround the leg, just below the knee, and provided with some form of fastening. If the fastening be a button and button hole, it must be so loose as to be 30 slightly and uncomfortable, or, if tight enough for present comfort, and appearance, then when the position of the body is changed, the muscles and tendons of the leg so change their size and position that 35 the fastening is unduly tight.

I have heretofore sought to overcome the difficulty by inventing a yielding fastener located in a pocket, which still seems the 40 preferably way; but I find that nearly as good a result may be also attained by substituting a bridge piece in place of a complete pocket, and a garment with such feature is the subject of this application, which may almost be termed a division of my 45 former one.

1 indicates the leg of the garment, 2 the band usually employed, though I might make one without a band, 3 is one flap of the opening and 4 the other flap.

50 The garment is preferably so proportioned and so cut and stitched that one flap will lie over the other.

On one flap say 3, I secure one element 55 of a fastening device, for instance, one or more eyelets 5, preferably mounted upon a reinforcing strip 6. On the other flap say

4, and a considerable distance from the flap edge, I secure an elastic band 7. The band might be made up of sections one of which was elastic and one inelastic, but no good 60 purpose is thereby promoted.

I make the elastic part of the band or securing device of considerable length, in order that its continued extension and contraction shall not so quickly destroy its elastic 65 character.

If a very short piece of elastic is used, then it is stretched so near the limit of its capacity, at any movement, that its life is very short and I avoid that difficulty by 70 using a piece of considerable length.

One end of the elastic (or two ends if it is looped) is secured to the material of the garment. This may be done by sewing it directly to the material, or to the band 2, if 75 there be one, or to a tape 8, which is in turn secured to the garment, the essential feature being that the elastic shall in some way be secured to the garment so as to aid in fastening it and that the fastening shall 80 be at a distance from the edge, sufficient to permit an elastic of material length to be used, that is, one that is considerably longer than the difference between the normal measure of the limb and its dimension when most 85 distended.

On the free end of the elastic member, I secure a fastening complementary to the one on the other flap. In this embodiment it is a hook 9, but I could secure the hook to 90 strip 6, and an eyelet to the elastic 7.

The devices thus far described would secure the garment but not neatly. The flap 4 would fly open and, being loose, would be more or less objectionable, particularly to 95 boys. In my fastening, I have therefore provided for that feature also, by passing a bridge 10 over the elastic near the edge of the flap and yet within the line of the hook end. It is secured to the tape 8, or the band 100 or the garment, and permits the elastic to be extended under it or to retract freely and yet when the hook is engaged in the eyelet, in the form shown, it will hold the flap 4 closely to the flap 3, which is the end desired. 105

Instead of the narrow bridge 10, I may use a broad bridge 11. The distance it extends laterally is not limited, provided its forward line is so placed as to properly hold the elastic.

110 The entire combination exhibits a garment which may be readily unfastened for re-

removal or assumption, may be readily secured when assumed, and so secured as to be neat in appearance, comfortable in fit, to have the flap held down as desired and yet be susceptible of yielding to the motions of the body as desired, and the ends sought are attained by means which are durable, because seldom or never strained to the limit, though not likely to be strained beyond further service, by even an unusual call upon their yielding capacity.

What I claim as my invention and desire to secure by Letters Patent, is:—

In knee breeches, a knee band, fastening means for the ends thereof, a plurality of one member of the fastening means being disposed on one end of the band, a strip of strong material attached to the other end

of the band, an elastic tongue attached to the strong material at a point remote from the edge of the band, a fastening member attached to the projecting end of the tongue and mating with the fastening members disposed at the other end of the band, and a bridge of strong material extending across the elastic tongue and supporting it and fixedly secured to the material of the band, between the point where the elastic tongue is secured and the proximate end of the band.

Signed at New York in the county of New York and State of New York this 8th day of November A. D. 1912.

ISAAC SCHEINMAN.
